UNITED STATES PATENT OFFICE

2,503,090

CIGARETTE DISPENSER

Stanley C. Both, Hamburg, N. Y.

Application September 10, 1946, Serial No. 695,970

4 Claims. (Cl. 312—80)

1

My present invention relates generally to improvements in portable dispensing cabinets, for slender cylindrical articles, employing a horizontally reciprocating ejector, and more specifically to a cigarette dispenser of the manually operated type, which is simple in construction in order to assure smooth and reliable operation in the ejection of a cigarette from a supply of cigarettes contained in bulk within an interior hopper of the cabinet.

The cabinet or enclosure, as a whole consists of a minimum number of parts that may readily be manufactured and compactly assembled; and the ejecting mechanism, together with agitating means for the cigarettes, also includes a minimum number of parts that may with convenience be assembled, mounted in operative position, and installed within the cabinet, for efficient performance of its functions.

The invention consists in certain novel combinations and arrangements of these parts as will hereinafter be more fully set forth and claimed. In the accompanying drawings I have illustrated one complete example of the physical embodiment of my invention wherein the parts are combined and arranged in accord with one mode I have thus far devised for the practical application of the principles of my invention in a cigarette dispenser. It will be understood that various changes and alterations may be made in the exemplifying drawings and mechanical structures, within the scope of my appended claims without departing from the principles of my invention.

Figure 1 is a view in side elevation of a cigarette dispenser in which my invention is embodied, indicated by dotted lines the position of an ejected cigarette; and Figure 2 is a front elevation of the device in Fig. 1.

Figure 3 is a vertical, longitudinal, sectional view of the device, as at line 3—3 of Fig. 2.

Figure 4 is a sectional view similar to Fig. 3, but showing the ejecting mechanism with the cigarette in ejected position.

Figure 5 is a transverse sectional view through the cabinet, as at line 5—5, showing the mechanism in ejecting position.

Figure 6 is a front elevation of the device, with the front plate removed, as at line 6—6 of Fig. 4.

Figure 7 is a transverse sectional view at line 1—7 of Fig. 6.

Figure 8 is a top plan view of the base; and Figure 9 is a front elevation of the base for the hopper or housing.

Figures 10 and 11 are respectively a front view and a side view of the combined feeding, agitating, and ejecting device of the ejecting mechanism.

Figure 12 is a fragmentary sectional view of the slide plate and the mounting therefor.

For convenience in illustration and description

2

I have referred to the invention as embodied in a dispenser for cigarettes, but it will be understood that the dispenser may readily be adapted for vending or dispensing other similar articles, and the scope of my invention is therefore not limited to a cigarette dispenser per se.

As here illustrated I employ a cabinet or enclosure that includes an integral housing 1 molded, pressed or otherwise fashioned of suitable material, having vertical side walls and rounded top, in which an open end hopper 2 is formed and adapted to accommodate approximately two packs of cigarettes C in bulk, and from which the cigarettes are to be ejected singly.

15 The bottom 3 of the hopper is depressed, with convex surfaces into a central longitudinally extending trough 4 of size and shape conforming to the contour of the cigarette, and a short narrow vertical slot 5 is provided which extends from the open rear end of the trough a suitable distance to accommodate the ejecting mechanism.

20 The convex bottom of the hopper is also provided with a pair of longitudinally extending, front, vertical slots 6, 6, one at each side of the central trough 4, which slots open at the top into the interior of the hopper, and they also open at the bottom below the bottom of the hopper.

25 The bottom of the hopper is elevated above the lower edges of the side walls 7 of the housing, 30 and these side walls are mounted upon a horizontal base block 8, which is molded, pressed or otherwise fashioned of material suitable for that purpose, and the base or base block is provided in its upper face with open end spaced and parallel grooves 9, 9; and a central elevated groove 10 35 that is located at the rear of the base directly beneath the slot 5 of the housing for accommodation of part of the ejector mechanism.

40 The front of the housing or cabinet is closed by means of a face plate 11, preferably of metal, having a delivery or dispensing aperture 12 that is aligned with the trough of the hopper, and the rear end of the cabinet is closed by a back plate 13, having dovetail vertically extending flanges 45 14 that accommodate and guide the movement of a detachable slide plate 15. The slide plate may be lifted to open position to permit filling of the hopper with a supply of cigarettes in bulk, and of course the supply may be replenished when a preceding one has been consumed.

45 The housing and the base when assembled are rigidly united in suitable manner, and the end plates are fastened to the housing and base, as by attaching screws, to provide a stable cabinet or enclosure for the cigarettes and the dispensing mechanism.

50 As indicated in Fig. 6 the cigarettes, in bulk and loosely arranged, are contained within the hopper with the lowermost cigarette in the trough 4, 55 at the bottom of a vertical column of cigarettes

60 at the bottom of a vertical column of cigarettes

that are in position to be fed successively into the trough, for ejection therefrom, and other cigarettes are supported on the depressed bottom of the hopper. These latter cigarettes, when unobstructed, are also adapted to roll down the convexly curved and opposed faces of the depressed bottom, and thus, singly, be fed into the trough 4, for ejection therefrom.

The ejecting mechanism, which also causes agitation of the cigarettes to prevent jamming, and feeding of the cigarettes to the ejection trough, is manually actuated by use of either or both handles 16, 16 that project from opposite sides of the cabinet, and the handles are conveniently formed by curling the ends of a crank pin or bar 17 which is mounted to rock in bearing holes formed by grooves 18 in the adjoining faces of the housing and the base block.

The crank pin or rock bar extends transversely through the cabinet, near its front end, and it is provided with fixed collars 19, 19, to retain it in operative position and prevent excessive transverse movement. A pair of laterally spaced rock arms 20, 20 are soldered, brazed, or welded rigidly on the rock bar and located in position to swing in the grooves 9 of the base and in the space beneath the elevated bottom of the hopper, and a U-shaped yoke 21 is pivotally connected at 22, 22, with the free ends of the rock arms.

On the connecting arm of the pivotal U-shaped yoke a slide block or ejecting block 23 is pivotally mounted to reciprocate horizontally upon the central elevated portion of the base block, and an L-shaped ejector 24 is rigidly secured to and travels with the slide block. The ejector projects upwardly, from groove 10 of the base block, through the vertical slot 5 of the bottom of the hopper or its trough, and the upper end of the ejector is fashioned with a suitable ejecting head 25 alined with and adapted to travel forwardly and backwardly through the trough 4 in the bottom of the hopper.

The handles 16 and the rock arms 20 radiate in the same plane from the rock bar 17 in order that the position of the ejector may readily be determined from the exterior of the cabinet. By swinging the normally upright handles backward, the ejector is retracted; and by swinging the handles forward toward the front of the cabinet the ejector is projected to eject the lowermost cigarette C through the front delivery opening or aperture 12, as indicated by dotted lines in Figs. 4 and 5.

The sliding movement of the ejector block is guided by means of spaced guide plates 26, 26, that are fastened at opposite sides of the block and project above and below the block, as shown, the lower edges of the plates coating with the sides of the central elevated portion of the base block.

For performing the dual functions of agitating the cigarettes in the hopper to prevent jamming, and to form a chute for gravity-feeding the cigarettes in a vertical column down to the trough 4 of the hopper, I provide a pair of vertically arranged, laterally spaced, cam plates 27, 27, that project upwardly through the two slots 6, 6, in the bottom of the hopper. These plates are retained within the walls of the slots against longitudinal movement with the ejector block, but they are mounted on the plates 26 of the slide block to have a vertically reciprocating movement

on the slide block and through the slots 6 of the housing.

For this purpose the plates 26 are provided with complementary angular cam slots 28 extending generally in a horizontal direction, and screws 29 are passed through the cam slots and threaded into the respective cam plates 27. The lower edges of the cam plates are fashioned with oblique or diagonal cam faces, and the slide block is fashioned with complementary cam faces 31 in its upper face.

From this description it will be apparent that as the slide block reciprocates horizontally, its movement causes the cam plates to reciprocate vertically through slots 6, 6, into the lower portion of the hopper, and this reciprocating movement of the cam plates agitates the contained cigarettes, and intermittently forms a vertical column of cigarettes supported from the trough 4.

Having thus fully described my invention, what I claim as new and desire to secure by Letters Patent is:

1. In a cigaret dispenser having a feed hopper, an ejecting trough, and an alined aperture, the combination with an ejector having a head alined with the trough, and means for reciprocating the ejector, of vertically reciprocable means disposed at opposite sides of the trough and movable into the hopper to form a chute to the trough, and means actuated by the ejector for reciprocating said means to form the chute.

2. The invention as in claim 1 wherein said ejector is mounted on a reciprocable block and the means for reciprocating the ejector comprises a U-shaped yoke pivotally mounted in the block, a transversely arranged rock-bar journaled beneath the trough, a pair of inner rock-arms pivoted to the yoke, and a pair of crank-arms exterior of the dispenser and radially alined with the rock arms for actuating the rock-bar.

3. In a cigaret dispenser having a feed hopper, a horizontal bottom-trough, and an aperture, the combination with an ejector having a head alined with the trough and aperture, and means for reciprocating the ejector, of a pair of vertically reciprocable chute- plates movable in bottom-slots at opposite sides of the trough into the hopper, and coating cam-actuated means on the ejector and said plates for translating horizontal movement of the ejector into vertical movement of the plates.

4. In a cigaret dispenser having a feed hopper, a horizontal bottom trough, and an aperture, the combination with an ejector having a head alined with the aperture and trough, and means for reciprocating the ejector, of a pair of vertically reciprocable chute plates movable in bottom-slots at opposite sides of the trough into the hopper, means for mounting the plates on the ejector, and coating cams on the plates and block for translating horizontal movement of the ejector into vertical movement of the plates.

STANLEY C. BOTH.
